CLAIM

The ornamental design for a heated apparel controller, as shown and described.

DESCRIPTION

FIG. 1 is a perspective view of a heated apparel controller in accordance with the present invention;

FIG. 2 is a first side view of the heated apparel controller shown in FIG. 1;

FIG. 3 is a second side view of the heated apparel controller shown in FIG. 1;

FIG. 4 is a top view of the heated apparel controller shown in FIG. 1;

FIG. 5 is a bottom view of the heated apparel controller shown in FIG. 1;

FIG. 6 is a third side view of the heated apparel controller shown in FIG. 1; and,

FIG. 7 is a fourth side view of the heated apparel controller shown in FIG. 1.

The broken lines are for illustrative purposes only and form no part of the claimed design.

The cable is shown broken away in the drawing views to indicate indeterminate length, it being understood that it has a uniform shape and appearance through its length.
